US00D756318S

(12) **United States Design Patent**
Kim et al.

(10) **Patent No.:** US D756,318 S
(45) **Date of Patent:** ** May 17, 2016

(54) **TELEVISION RECEIVER**

(71) Applicant: **LG Electronics Inc.**, Seoul (KR)

(72) Inventors: **Taeho Kim**, Seoul (KR); **Namhun Kim**, Gyeonggi-do (KR); **Yoonkyeong Lee**, Seoul (KR); **Junki Kim**, Seoul (KR); **Ilsub Yoon**, Seoul (KR); **Dongwon Choi**, Seoul (KR); **Kyoyoon Koo**, Seoul (KR)

(73) Assignee: **LG Electronics Inc.**, Seoul (KR)

(**) Term: **14 Years**

(21) Appl. No.: **29/460,726**

(22) Filed: **Jul. 15, 2013**

(30) **Foreign Application Priority Data**

Jan. 15, 2013 (KR) 30-2013-0002443
